UNITED STATES PATENT OFFICE.

AUSTIN ADAMS, OF NEW YORK, N. Y.

HOLDER FOR DOORS.

SPECIFICATION forming part of Letters Patent No. 595,428, dated December 14, 1897.

Application filed January 14, 1896. Serial No. 534,934. (No model.)

To all whom it may concern:

Be it known that I, AUSTIN ADAMS, a citizen of the United States, and a resident of New York, in the county and State of New York, 5 have invented a Latch or Door-Holder, of which the following is a specification.

My invention relates to appliances designed for the purpose of holding or temporarily fastening in one position movable structures—as, 10 for example, securing of doors, &c., in an open relation; and it has for its object the provision of a device simple in construction, inexpensive in manufacture, and efficient in practical use.

15 To attain the desired end my invention consists in the construction and arrangement of parts first fully set forth, and then pointed out in the claims.

In the drawings which form a part of this 20 specification, Figures 1 and 2 represent perspective views of my holding device respectively held in an open and closed relation. Fig. 3 is a plan view, and Figs. 4 and 5 are respectively a side elevation and a perspective 25 view of my keeper.

Referring again to the drawings, A denotes one member of my door-holder, consisting of a pivoted or swinging latch, as an arm provided with a collar A', movably secured there- 30 to, and constructed and arranged to be normally held in a certain position, as by means of a weight, as the ball A³, located at the extremity of the swinging latch A². The other member of my appliance consists of a keeper 35 or holder for the arm A, &c., which keeper is preferably provided with a hollow or open interior portion and is ordinarily constructed in tubular form, as B. The exterior face of my keeper is provided with an inclined way 40 or edge B', ordinarily formed by cutting a spiral or helical groove in the said face, which terminates in the groove B². The outer end of my keeper is preferably formed with an orifice sufficiently large to admit the entrance 45 of the arm A therein, the said orifice being eccentric as regards the longitudinal axis of my tubular keeper B and communicating with the spirally-formed groove heretofore described, which groove terminates in a locking 50 recess or cavity B³. This recess is preferably located in line with the inclined edge

B' in front of the same, as shown in Figs. 4 and 5.

It will thus be seen that my invention consists in two relatively movable members of 55 the combination, with one member provided with a pivoted or swinging latch and another member comprising a hollow tubular keeper provided with an upwardly and rearwardly inclined spiral edge terminating in a down- 60 wardly and forwardly inclined slot or way, whereby the movable members may become locked by a forward movement of the same and unlocked by a slight forward-and-backward movement of the said member. 65

In operation the arm A is entered into the orifice of the keeper, and on account of the eccentric location of the same the latch is caused to ride on the inclined edge on short leverage until at rest in the forwardly and 70 downwardly inclined slot, and the door, &c., is thereupon held in an open relation by means of the said engagement of the two members of my appliance. When it is desired to disengage the said members, as to pull the door 75 shut, a motion toward the back of the door forces the swinging latch to the end of the depression or recess adjacent to the extremity of the inclined curve—namely, at the point b'—and by a quick pull the latch is thrown 80 to the inclined way B', whereupon the latch rides upon and off the said edge on a long leverage, an easy action in releasing the two members of my appliance from engagement 85 and the door from the keeper being thereby secured.

As it is evident that many slight changes in the construction and relative arrangement of parts might be resorted to without departing from the spirit and scope of my invention, 90 I would have it understood that I do not restrict myself to the particular construction and arrangement of parts shown and described, but that I reserve the right to make such changes, and that— 95

What I claim as new, and desire to secure by Letters Patent, is

1. In a fastening device, the combination with one member, provided with an upwardly and rearwardly inclined spiral edge or way, 100 terminating in a downwardly and forwardly inclined edge or way, of another relatively

- movable member, and means for retaining said movable member in engagement with said latter edge or way whereby the members may be engaged by a forward movement of the object to be fastened, and unlocked by a slight forward-and-backward movement of the said object.
2. In a fastening device consisting of two relatively movable members, the combination with one member provided with a pivoted or swinging latch of another member comprising a hollow tubular keeper provided with an upwardly and rearwardly inclined spiral edge terminating in a downwardly and forwardly inclined slot or way whereby the movable member may become locked by a forward movement of the same and unlocked by a slight forward-and-backward movement of the said member.

3. A hollow tubular keeper provided with an upwardly and rearwardly inclined spiral edge terminating in a downwardly and forwardly inclined slot.

4. A hollow tubular keeper provided with an upwardly and rearwardly inclined spiral edge and terminating in a downwardly and forwardly inclined slot, and also formed with an intermediate depression or recess between said spiral edge and inclined slot, as specified.

In testimony of the foregoing specification I do hereby sign the same, in the city of New York, county and State of New York, this 28th day of August, A. D. 1893.

AUSTIN ADAMS.
